ROBERT MIEHLE, OF CHICAGO, ILLINOIS, ASSIGNOR TO MIEHLE PRINTING PRESS & MANUFACTURING COMPANY, OF CHICAGO, ILLINOIS, A CORPORATION OF ILLINOIS.

TRIPPING MECHANISM FOR PRINTING-PRESSES.

1,081,320.

Specification of Letters Patent.

Patented Dec. 16, 1913.

Application filed October 9, 1906. Serial No. 338,144.

To all whom it may concern:

Be it known that I, ROBERT MIEHLE, a citizen of the United States, residing at Chicago, in the county of Cook and State of Illinois, have invented certain new and useful Improvements in Tripping Mechanisms for Printing-Presses, of which the following is a full, clear, and exact specification.

This invention relates to tripping mechanisms for multi-cylinder printing presses, and especially for the type of press known as a two-color press, in which the same side of the sheet receives two successive impressions from the cylinders respectively.

15 In tripping mechanisms it is desirable that the construction be such that the tripping of one of the cylinders will follow automatically at a later and definite period with reference to the time of tripping the other, and that either cylinder may be tripped separately or independently of the other. Such character of tripping mechanism has heretofore been applied to two cylinder printing presses, as shown in the United States Patent issued to me dated December 24, 1901, No. 689,505.

The primary object of this invention is to provide an improved tripping mechanism of the described character for plural cylinder multi-color presses, or presses having a plurality of cylinders for respectively printing a portion of the same side of the sheet.

With a view to the attainment of these ends and the accomplishment of certain other objects which will hereinafter appear, the invention consists in the features of novelty in the construction, combination and arrangement of parts, which will now be described with reference to the accompanying drawings, and then more particularly pointed out in the claims.

In the said drawings, Figures 1 and 2 are side elevations, partly in section, showing respectively, opposite sides of a portion of a printing press provided with these improvements, with the parts in the position which they assume when both trip keys or pedals are depressed for the purpose of tripping the cylinders when the first cylinder is at the sheet receiving position. Figs. 3 and 4 are side elevations, similar to Figs. 1 and 2, showing the parts in the position they assume after the trip keys have been released and raised to their elevated position and

the cylinders have each made just one complete revolution from the position shown in Figs. 1 and 2. Fig. 5 is a vertical cross-section taken on the line $x-x$, Fig. 4. Figs. 6 and 7 are side elevations, similar to Figs. 1 and 2, showing parts in the positions they occupy at the time that the dog 30 of the cylinder elevating and lowering mechanism of cylinder 4 has moved a short distance on its downward movement. Figs. 8 and 9 are, 65 respectively, underneath view and side elevation of a portion of the tripping mechanism when the parts are in the position shown in Fig. 1. Figs. 10 and 11 are sectional views showing the bent arm 54 in 70 different positions.

In cylinder printing presses, where the cylinder undergoes a rising and falling motion with reference to the bed, the cylinder raising and lowering mechanism 75 usually embodies a spring for moving the cylinder in one direction, and positive means, such as an eccentric or toggle, for moving it in the other direction, and the spring is usually employed and is preferably employed in this instance for producing the upward movement. One or more springs, as shown at 1, 2, are used for each of the cylinders 3, 4, whose journals 5 are supported in boxes 6 arranged in suitable guides or 85 jaws 7, respectively.

Between the impression cylinders 3, 4, is arranged the transferring cylinder 8, which serves to transfer the sheet from the first cylinder 3 to the second cylinder 4, in a way 90 which will result in the second cylinder producing an impression upon the same side of the sheet as that upon which the first cylinder produced its impression. The transferring cylinder is driven by a gear 9, and has a 95 smaller gear 10 meshing with gears 11, 12, on the cylinders for imparting rotary motion to the latter. Gear 9 is driven by gear 13, on shaft 14. The shaft 14 drives cam 15, which actuates the cylinder lowering 100 mechanism of the first cylinder, through the intermediary of an idler 16 and pinion 17, while the gear 13 drives cam 18 of the cylinder lowering mechanism of the second cylinder, through the intermediary of idler 105 19, pinion 20, idler 21 and pinion 22, the peripheries of cams 15, 18, being provided with gear teeth for engagement with idler 16 and pinion 22, respectively. The arrangement of teeth in the several gears which 110

drive cams 15, 18 is such that the two cams move in unison, each making one complete revolution for each sheet printed.

The cylinder lowering and tripping mechanisms for the two cylinders are very similar in construction and operation, the differences consisting, mainly, in the means whereby the tripping of the second cylinder is deferred after the tripping devices are released until the sheet which was printed by the first cylinder passes and receives an impression from the second cylinder. Because of the similarity of the lowering and tripping mechanisms of the two cylinders, in describing these mechanisms, the same letters of reference will be employed where corresponding parts are identical, and it will be understood that the description applies equally to the mechanism of each of the cylinders.

Above the boxes 6 of the cylinders 3-4, are arranged eccentrics 23 resting in bearing blocks 24 and serving to lower the cylinders into impression or printing positions when said eccentrics are rotated in their bearing blocks, and this may be done through the agency of crank arms 25 and connecting rods 26 whose lower ends are pivoted to crank arms 27 rigidly secured to rocker shafts 28. It will be understood that one of the crank arms 27 is secured to each end of each rocker-shaft 28; (see Fig. 5) and that when a shaft 28 is rocked these arms through the medium of their respective connecting rods 26 communicate motion to both ends of the journals or shafts 5 of the cylinders 3-4, respectively.

Mounted securely, upon each of the rocker shafts 28, is a tooth 29, adapted to be engaged by a dog 30 having a notch 31 formed at or near its lower or free end and arranged to drop over and engage the tooth 29 while the other end of the dog is pivoted to the free end of a crank arm 32 loosely journaled or pivoted upon the shaft 28 so as to be capable of independent oscillation. 33 is a pin or stop to limit the upward movement of the tooth 29.

The necessary oscillatory motion of the arms 32 and dogs 30 which through the medium of the teeth 29 give the required rocking movement of the shafts 28, is produced by the cams 15, 18 each of which is provided in one face with a cam groove comprising a concentric or dwelling portion 34 and deflecting or active portions 35, 36. Each crank arm 32 is provided with a pin or anti-friction roller 37 adapted to engage into the groove of its corresponding cam so that when the cams are rotated in the direction of the arrows the arms 32 will be oscillated and, through the medium of the dog 30 and tooth 29, the shaft 28 be rocked for the purpose previously described. Referring now particularly to the cylinder

lowering devices of cylinder 3, of which, in Fig. 2, the dog 30 is shown in its upper or retracted position, when the cam 15 is rotated in the direction of the arrow, the dog 30 will be lowered to the position shown in Fig. 4, while the roller 37 is passing through the portion 35 of the cam groove and will be held in such lowered position while the concentric or dwelling portion 34 of the cam is passing the roller 37. While this concentric portion 34 is passing, the cylinder is at the limit of its downward movement and the impression is taking place. When the portion 36 of the groove arrives at the roller the dog 30 begins to rise, and when the roller arrives at about midway in the groove 36 the grippers 59 have arrived at about the position 59^a, shown in Fig. 1, and the sheet will be transferred to the transfer cylinder at the time when the cylinder 3 is in its midway position of its rising movement, and continues to rise until the portion 35 of the cam groove again arrives at the roller. The action of cam 18 of the cylinder lowering devices of cylinder 4 is the same as that of cam 15 last described, except that the active portion 35 is divided into lower and upper parts 35^a-35^b with a concentric or dwelling portion 35^c to be hereinafter more particularly referred to, separating the two active parts 35^a-35^b.

On one face of each of the dogs 30 is a lug or pin 38, projecting laterally therefrom into a groove 39 formed in the contiguous face of a cam arm 40 whose lower end is secured to a rod 41. The groove of each cam arm is, for the major portion of its length, concentric with its corresponding shaft 28, so that the lugs 38 ride idly to and fro in the grooves of their corresponding cams except when a cam arm 40 is oscillated upward, and, in that event, when lug 38 arrives about at the limit of the upper end of its groove 39, it engages a cam portion 42 formed within the groove thereby lifting the said roller and its dog 30 out of lock with its tooth 29 and permitting the dog to be moved downwardly by the arm 32 on the next stroke of the arm without carrying with it the tooth 29. When dog 30 is thus disengaged from its tooth 29 its corresponding cylinder 3 or 4 will be tripped and held in its elevated position out of impressing position by the springs 1-2, while the arms 32 and dog 30 may continue their rocking movements, and this tripped condition will exist until the notch 31 again returns to the limit of its upward stroke and drops over its tooth 29; it being understood, of course, that the tripped condition of a cylinder may be prolonged indefinitely so long as a cam arm 40 remains in its oscillated or upper position.

Having now described that portion of the cylinder lowering and tripping mecha-

nisms which are similar in their respective operations, I will now describe the actuating means by which the tripping devices are put into operation. On the rod 41 of the 5 tripping devices for the first cylinder is secured a lever 43 provided with an operating key 44 arranged in a position accessible to the press attendant, and adapted, when depressed, to rock the rod 41 and cam 40 and to move the upper end of the arm 40 upwardly with respect to the lug 38 for the purpose hereinbefore described. On the rod 41 of the tripping devices for cylinder 4 is secured a lever 45 carrying at 15 its free end a stud 46 whose outer end is provided with an anti-friction roller 47 adapted to be engaged by a cam 48 arranged to turn in unison with the cams 15-18 and which is preferably mounted 20 upon a shaft 49 upon which the cam 15 is also mounted. The stud 46 is arranged to move laterally in its bearing in the lever 45 whereby the outer end of the stud may be alternately brought into alignment with 25 the cam 48 as in Fig. 11 or thrown out of alignment therewith as in Fig. 9. So long as the stud 46 is not in alignment with cam 48 the tripping device is not actuated, but when it is desired to actuate the tripping devices, the stud 46 is moved into alignment with the cam 48 whereupon the elevated part 50 of the cam 48, which turns in the direction of the arrow, contacts with the stud 46 and depresses it and the lever 35 45, thereby rocking the rod 41 and arm 40 to move the upper end of arm 40 upwardly with respect to the lug 38 for the purpose previously set forth.

Mounted loosely upon the rod 41 of the 40 tripping devices for cylinder 3 is a crank lever 51 connected to a key or operating treadle 52 arranged in a position accessible to the press attendant and preferably placed so close to the key 44 that both keys 45 may be depressed at one time or may be depressed independently when so desired. The depending arm 53 of the crank lever 51 is adapted to engage a bent arm 54 through the medium of a flexible rod 55 50 carried by the arm 53. The arm 54 is loosely mounted upon a support 56 and its upper or bent end is arranged to contact with the inner end of the stud 46. Normally the arm 54 and stud 46 occupy the 55 position shown in Fig. 9 with the stud out of alignment with the cam 48, but when the key 52 is depressed the crank arm 51 is rocked throwing the inner end of its arm 53 upward, thereby tilting the arm 54 and 60 forcing its upper end against the stud 46 and moving the stud into alignment with cam 48 (see Fig. 10). Upon the release of the key 52 the bent arm 54 falls into its normal position in Fig. 11 leaving the stud 65 46 still in alignment with the cam 48. To

move the stud again into its normal position, a laterally projecting lug 57 is provided on the cam 48 which by contacting with the inner end of the stud 46 moves the stud outward to its normal position, Fig. 9. 70

58-58^a are coil springs adapted to return the levers 43, 51 and the keys 44, 52, to their normal positions when the pressure upon the keys is removed. 75

When the cylinders 3-4 are to be tripped it is necessary, after the cylinder 3 is tripped, that sufficient time elapse before the cylinder 4 is tripped for the sheet last printed by cylinder 3 to pass 80 from cylinder 3 and to be received therefrom by and to pass one and one-half times around the transfer cylinder 8 and thence to pass to and to be printed by cylinder 4. The cylinders 3, 4, may be tripped at the 85 desired times successively by first pressing the key 44 of the tripping devices of cylinder 3 and then, at the proper time thereafter, depressing the key 52 of the tripping devices of cylinder 4. Such independent manipulation of the operating keys requires 90 much care on the part of the operator, making the operation of the machine unnecessarily complex. I prefer to simplify the operation of the tripping devices by pressing both keys 44-52 at the same instant, and, when this is done, they should be pressed at or about the time that the parts are in the position shown in Figs. 1-2 when the cylinder 3 is in its raised position, and 95 when the tooth 29 of the cylinder elevating and lowering mechanism of cylinder 3 is in its upper position, as in Fig. 2, and, at this time, the grippers 59 of cylinder 3 are 100 in the position shown in Fig. 1, ready to 105 receive a sheet from the feed board 60, although, if the press is to be tripped, it is not usual to supply a sheet to the grippers 59 at this turn of the cylinder. The depressing of the key 44 causes the cam-arm 40 110 of the tripping devices of cylinder 3 to be oscillated upward and thereby force its cam portion 42 against the lug 38 on dog 30 to lift the dog out of lock with the tooth 29, as in Fig. 2, and by depressing key 52 at 115 the same time with the key 44, the cam 48 has its lug 57 directly opposed to the outer end of stud 46, Figs. 1 and 8, and, while the lug is in this position it will not permit the stud 46 to be moved through its bearing 120 in the lever 45 but retains the stud and bent arm 54 in their normal position (Fig. 9) and thereby prevents the outer end of the rod 55 from being raised, when the lever 51 is rocked by the key 52, but causes the rod 125 to assume, temporarily, the bent position shown in Fig. 1. As soon, however, as the cam 48 has turned in the direction of the arrow, so far as to remove its lug 57 out of contact with the stud 46, for instance, into 130

the position shown by dotted lines in Fig. 1, the spring tension of the rod 55 causes it to straighten into the position shown by dotted lines in Fig. 1 thereby raising its free end to tilt the arm 54 and force the stud 46 inward through its bearing in the arm 45 and into alinement with cam 48 as in Fig. 10. It is usual, as soon as the stud 46 has thus moved inward and after the dog 30 of the cylinder elevating and lowering mechanism of cylinder 3 has moved downward so far that it cannot again drop over the tooth 29, to remove the pressure from the keys 44, 52, and this happens at about 10 the time that the grippers of cylinder 3 have moved to the position shown by dotted lines at 59^a in Fig. 1. When the trip keys are thus released the levers 43, 51 and arm 54 assume their normal position while the stud 20 46 remains in alinement with cam 48, as in Fig. 11; the cam arm 40 of the tripping devices of cylinder 3 also, at this time, returns to its lower or normal position and drops its cam portion 42 below the path 25 of movement of the lug 38 on dog 30 whereby when the dog again moves to the upper end of its movement its notch 31 may again drop over the tooth 29 in position to further operate the cylinder elevating and lowering mechanism of cylinder 3, but the cam arm 40 of the tripping devices of the second cylinder has not as yet been moved from 30 its normal position.

As the cam 48 continues to turn, after the proper interval for the passing of the sheet last printed by cylinder 3 to cylinder 4 and to be printed thereby the elevated or high part 50 of the cam reaches the stud 46 and depresses it and the lever 45 and oscillates 35 upward the cam arm 40 of the tripping devices of cylinder 4. The initial or advance portion of the high part 50 of the cam 48 first operates on the stud 46 to oscillate upward the arm 40 at about the time 40 that dog 30 of the cylinder elevating and lowering mechanism of cylinder 4 has reached the end of its upward movement, and the upward oscillation of the lever 40, by forcing its cam portion 42 against the 45 lug 38 on the dog 30 lifts the dog out of lock with the tooth 29. The said high part 50 of cam 48 is of sufficient breadth to press upon and hold down the stud 46 until the dog 30 has moved so far on its downward 55 movement as to carry its notch 31 beyond and out of alinement with the tooth 29 as shown in Fig. 6.

When the key 52 is depressed, as stated, the parts being in the position shown in Figs. 1, 2, the dog 30 of the cylinder elevating and lowering mechanism of cylinder 4 is in about the middle of its forward or lowering movement while the roller 37 lies in the groove of cam 18 near the beginning of

the concentric part 35^c of said groove at 65 which time a sheet is just commencing to pass to cylinder 4 from the transfer cylinder 8. As the cam 18 is rotated in the direction of the arrow, the roller 37, while the sheet is being received from the transfer cylinder 70 8 by the impression cylinder 4, passes first through the concentric portion 35^c of the cam groove and then, as the cam is further rotated, the roller will pass through the outer active portion 35^b of the groove to 75 cause the dog 30 to complete its downward movement and the dog 30 will be held in such lowered position while the concentric or dwelling portion 34 of the cam is passing the roller 37. Fig. 4 shows the position of 80 these parts while the roller 37 is still in the portion 34 of the cam. While the concentric portion 34 of the cam is passing, the cylinder 4 is at the limit of its downward movement and an impression is being made 85 by that cylinder on the sheet just previously printed by cylinder 3. When the portion 36 of the groove arrives at the roller the dog 30 begins to rise and continues to rise until the portion 35^a of the cam groove again arrives at the roller whereupon the dog 30 commences its downward movement, as in Fig. 7.

As soon as the high part 50 of the cam 48 has passed over the stud 46 and into the position shown, by dotted lines in Fig. 6, the lever 45 is drawn, by the spring 61, upward into the position shown by dotted lines in Fig. 6, thereby permitting the arm 40 of the tripping devices of cylinder 4 to return to 100 its lower or normal position, whereby its cam portion 42 is brought below the pathway of lug 38 on dog 30, so that when the dog again arrives at the upper end of its movement its notch 31 will again drop over 105 the tooth 29 in position further to operate the cylinder elevating and lowering mechanism of cylinder 4. As the cam 48 further rotates its lug 57 operates on the end of the stud 46 to return to its normal position, as 110 in Fig. 9.

With the construction described, it will be seen that either of the cylinders may be tripped at will independently of the other by the depression of one or the other of the 115 keys 44, 52, or, if desired, the operator by pressing his foot upon the two keys simultaneously at the proper time and by maintaining the pressure only so long as is required to trip the first cylinder, may cause 120 the tripping of the second cylinder to occur through the intermediate mechanism herein shown at a predetermined period of time with respect to the time that the first cylinder is tripped.

The cam groove of the cam 18 for lowering the second cylinder 4, differs from the cam groove of cam 15 in that in addition to

having the dwelling or concentric portion 34 and the deflecting or action portions 35—36, it is formed with the dwelling or concentric portion 35° adapted to reach the 5 roller 37 at the time when the cylinder 4 is about midway between the limits of its rising and falling movement, and the cam 18 is so set with relation to the cam 15 that, when the cylinder 3 is at the limit of its 10 upward movement and near the termination of its up-dwell, cylinder 4 will be about midway between the limits of its rising and falling movement in the course of its downward stroke, the grippers 59 of the first cylinder 3 being at the position shown in Fig. 1, in readiness to receive a sheet, while the grippers 62 of the second cylinder 4 are in the position shown in Fig. 1, having just 15 closed upon a sheet and the grippers 63 of 20 the transferring cylinder having just released the sheet which is in the grasp of the grippers 62, the sheet at that time being still wrapped partially around the transferring cylinder. The purpose of this dwelling or 25 inactive portion 35° of cam 18, it will, therefore, be seen, is to permit the cylinder 4 to dwell in its descending motion while its grippers 62 are grasping the edge of the sheet coming from the transferring cylinder 30 and removing it therefrom, and the portion 35° of the cam 18 should be of sufficient length to cause the second cylinder 4 to dwell in its said middle position until all or nearly all of the sheet has been removed 35 from the transferring cylinder. It will also be seen that the second cylinder receives the sheet at this intermediate position of its rising and falling movement when the center of the cylinder 4 falls into a direct line with 40 the point of closest engagement between the teeth of gears 10—12 and the center of cylinder 11. These features of improvement relating to the transfer point of the sheet and also to the inclination of the guide jaws 7 45 of the cylinders, however, constitute the subject-matter of another application and form no part of the present invention, further than the particular form of the cam 18 is concerned.

50 What I claim as new is:

1. In a cylinder tripping mechanism for multi-cylinder printing presses, the combination of two cylinders, means for raising and lowering the first cylinder, means for 55 raising and lowering the second cylinder, means for alternation with the raising and lowering movement of the first cylinder, independent cylinder tripping means for the cylinders respectively, embodying separate operating keys arranged for simultaneous as well as 60 independent operation, said tripping means of the two cylinders being so related and timed that when they are moved simultaneously to tripping position that of the second

cylinder will trip after that of the first cylinder, retaining means for holding the tripping means of the second cylinder in tripping position, and means for releasing said retaining means at about the time of the second lowering movement of the said raising and lowering means of the second cylinder, reckoned from the time of the release of the tripping means of the first cylinder. 65

2. In a cylinder tripping mechanism for multi-cylinder printing presses, the combination of two impression cylinders, means for raising and lowering said cylinders in alternation, cylinder tripping means for the cylinders respectively, the tripping means for the second cylinder embodying a tripping cam, retaining means for holding said cam in tripping position, embodying a retaining cam and stud, and a releasing device movable with said retaining cam for disengaging said retaining cam and stud. 75 80

3. In a cylinder tripping mechanism for multi-cylinder printing presses, the combination of two impression cylinders, means for raising and lowering the cylinders in alternation, cylinder tripping means for the cylinders respectively, the tripping means for the second cylinder embodying a tripping cam, a retaining cam for holding said tripping cam in tripping position, having a notched periphery, a retaining stud movable into the plane of said cam operatively connected with said tripping cam, means carried by said retaining cam for engaging said stud and deflecting it out of its plane of said retaining cam when the stud drops 100 into said cam. 85

4. In a cylinder tripping mechanism for multi-cylinder printing presses, the combination of two impression cylinders, means for raising and lowering the cylinders in alternation, cylinder tripping means for the cylinders respectively, the tripping means for the second cylinder embodying a tripping cam, a retaining cam for holding said tripping cam in tripping position, a stud operatively related to the tripping cam and movable into and out of engagement with its retaining cam and means carried by the retaining cam for shifting said stud. 105 110

5. In a cylinder tripping mechanism for multi-cylinder printing presses, the combination of the first and second impression cylinders, a transferring cylinder, sheet grippers on all of said cylinders, gearing connecting all of said cylinders together, 120 and means for raising and lowering each of the impression cylinders, the raising and lowering means for the second cylinder embodying means for causing the cylinder to dwell in its rising and falling movement at an intermediate point in such movement when the grippers of the transferring cylinder and of the second impression cylinder 125

are contiguous, and means for tripping said cylinder raising and lowering means.

6. In a cylinder tripping mechanism for multi-cylinder printing presses, the combination of two impression cylinders, means for raising and lowering the cylinders in alternation, cylinder tripping means for the cylinders respectively, a retaining cam for holding the tripping means of the second cylinder in a tripping position, a stud operatively related to the said tripping means of the second cylinder for thus holding it in tripping position and being movable into and out of engagement with said retaining 10 cam, an actuating means for forcing said

stud into engagement with the retaining cam, embodying an elastic medium whereby the actuating means may be operated in advance of the time of the movement of the stud, and means operating in unison with 20 the retaining cam for forcing the stud out of engaging position therewith.

In testimony whereof I have signed my name to this specification, in the presence of two subscribing witnesses, on this 4th day 25 of October A. D. 1906.

ROBERT MIEHLE.
